US0D1025092S

(12) **United States Design Patent** (10) Patent No.: **US D1,025,092 S**
 So (45) Date of Patent: ** Apr. 30, 2024

(54) **DISPLAY PANEL WITH GRAPHICAL USER INTERFACE**

(71) Applicant: **LG DISPLAY CO., LTD.**, Seoul (KR)

(72) Inventor: **Byeongseong So**, Paju-si (KR)

(73) Assignee: **LG DISPLAY CO., LTD.**, Seoul (KR)

(**) Term: **15 Years**

(21) Appl. No.: **29/826,425**

(22) Filed: **Feb. 11, 2022**

(30) **Foreign Application Priority Data**

Aug. 12, 2021 (KR) 30-2021-0038448

(51) **LOC (14) Cl.** **14-04**

(52) **U.S. Cl.**

USPC **D14/489**

(58) **Field of Classification Search**

(57) **CLAIM**

The ornamental design for a display panel with graphical user interface, as shown and described.

DESCRIPTION

FIG. 1 is a front view of a display panel with graphical user interface showing my new design; and, FIG. 2 is an enlarged view of a portion of FIG. 1. The broken lines depict portions of the display panel with graphical user interface that form no part of the claimed design.

1 Claim, 2 Drawing Sheets
